UNITED STATES PATENT OFFICE.

HARRY B. PRUDEN, OF CHICAGO, ILLINOIS, ASSIGNOR TO POWDERED COAL ENGINEERING & EQUIPMENT COMPANY, OF CHICAGO, ILLINOIS, A CORPORATION OF ILLINOIS.

COMMINUTED-FUEL CARBURETOR.

Application filed January 7, 1916, Serial No. 70,832. Renewed October 9, 1916. Serial No. 124,692.

To all whom it may concern:

Be it known that I, HARRY B. PRUDEN, a citizen of the United States, residing at Chicago, in the county of Cook and State of Illinois, have invented certain new and useful Improvements in Comminuted-Fuel Carburetors, of which the following is a specification.

This invention relates to carburetors for the carbonization of fuel, and especially to carburetors for comminuted material such as are used with burners of the type in connection with fire-boxes, fire-chambers or combustion chambers.

It has been discovered under actual working conditions that each particle of comminuted fuel, when surrounded by air and entering a fire-box, will ignite instantly and a complete combustion results therefrom, thereby eliminating soot, cinders, the residue being the small particles of ash only. Now, therefore, I have devised a carburetor for comminuted fuel which insures a complete combination of the oxygen of the air and the comminuted fuel under all service conditions. For instance, a feeder and nozzle which would produce a long flame, would not produce complete combustion under the best conditions, and would further fail to produce proper combustion when the length of the flame was reduced. It has been found that either incomplete combustion with the production of smoke resulted, or that clogging of the feeder, due to deposition of the comminuted material in the feeder, would take place.

The principal object of the invention is to provide an improved form of carburetor wherein the control of the admission of air and the comminuted material as well as the delivery of the thoroughly mixed air and fuel through the nozzle will be such as will insure perfect combustion under any and all conditions of service and use.

A second important object of the invention is to provide an improved means of mixing air and comminuted material in a device of this character.

A third important object of the invention is to provide improved means for assisting the feeding of the comminuted material to the mixing chamber.

A fourth important object of the invention is the provision of improved means for

controlling the rate of flow of the mixed air and comminuted material toward the outlet or nozzle of the device.

A fifth important object of the invention is the provision of improved means of controlling the flow of mixed material through such outlet or nozzle.

A sixth important object of the invention is the provision of a carburetor for comminuted material especially adapted to be used in connection with a supply of comminuted material removed from the storage and supply apparatus shown and described in my copending application filed of even date herewith and bearing the Serial Number 70,834.

A seventh important object of the invention is the provision of an improved form of carburetor which, while especially adapted to use in connection with the above apparatus, may yet have the comminuted material supplied when necessary by a screw or other mechanical conveyor.

With the above and other objects in view, the invention consists in general of certain novel details of construction and arrangements of parts hereinafter fully described, illustrated in the accompanying drawings, and specifically claimed.

In the accompanying drawings, like characters of reference indicate like parts in the several views, and:

Figure 1 is a longitudinal section through a carburetor constructed in accordance with this invention.

Figure 2 is a front elevation of the nozzle and body of such a carburetor.

Figure 3 is a top plan view of the complete carburetor.

Figure 4 is a detail section through a worm feed conveyor adapted for use here-with.

While the carburetor herein shown and described has been illustrated as being of certain general proportions and as possessing peculiar specific details, it is to be understood that the invention in itself is not confined to the exact proportions shown or precise details set forth, but covers in scope everything set forth in the claims.

In the embodiment illustrated, which is typical of one preferred form, there is provided an outer casing consisting of a shell or body 10 which is provided with outwardly

directed and inwardly converging frusto-conical ends 11. The rear end 11 is connected to an air supply pipe 12 which is preferably downwardly curved as at 13 and 5 then curved backwardly as at 14 so that it may be connected with any suitable source of supply of air under pressure, the latter not being deemed necessary to be shown as it forms no essential part of the invention. 10 It is also preferred that a suitable valve 15 be located in the curved portion 13, this valve serving to control the air supply to the outer casing.

Hermetically sealed to the front end 11 is 15 a cylindrical inner casing or shell 16 which is spaced from the outer body or shell 10. This inner casing is provided with circumferential rows of spaced diagonally directed openings or louvres 17, the louvres in one 20 row being directed in a direction at an angle to the louvres in adjacent rows so that air forced into the inner shell from the space between that shell and the outer shell will be set up into a tumultuous series of eddies 25 and will constantly agitate any comminuted material forced into the inner shell. It is also preferred that the extreme rear openings or louvres 18 shall be larger than the remainder so that there will be a constant 30 forward movement of the contents of the inner shell.

This inner shell terminates forwardly in a laterally expanded and vertically depressed extremity 18' carrying a delivery 35 nozzle hereinafter to be described.

Extending through the pipe 12 and bent to terminate axially within the rear end of the casing 16 is a comminuted fuel inlet pipe 19 or duct which receives its supply 40 from the device illustrated in my copending application number 70,834 above referred to, or from a mechanical source of supply such as is illustrated in Figure 4. Extending axially into the horizontal portion of this 45 fuel supply pipe 19 is the nozzle of an air supply jet pipe 21 which opens rearwardly into the pipe 12 and is provided at its rear end with a gate or valve 22.

Surrounding the front end of the pipe 19 50 and at the rear of the inner shell 16 there is provided an annular valve seat 23 on which is adapted to seat a valve 24 connected to a stem 25. This stem 25 is threaded through a box 26 and is provided on its outer end 55 with a controlling wheel 27 so that, by turning the wheel in one direction or the other, the opening between the valve 24 and its seat 23 may be adjusted to meet the desired conditions.

60 The delivery nozzle above referred to comprises a box 28 which is substantially rectangular in cross section with its upper and lower sides flaring forwardly. At the rear end of the box, at the upper and lower 65 sides, are hinged a pair of deflector plates

29 hinged at 29'. Both the upper and lower sides of the box are provided with internally threaded bearings 30 through which pass valve stems 31 carrying hand wheels 32 so that under rotation of these hand 70 wheels the front edges of the deflector plates may be caused to approach or recede.

It is preferred that the pipe 14 be used as the general air inlet for all of the apparatus, and one or more branch pipes 33 controlled 75 by valves or gates 34 may extend therefrom for the supply of air to the apparatus described in my copending application No. 70,833.

In using this apparatus it is to be kept in 80 mind that the pressure of air in the pipe 14 will be substantially constant. With a given opening of the valve 15 a substantially constant supply of air will be furnished to the pipe 12. This air will flow through the louvres 17 and 18 even when the valve 24 is closed and will there set up an intense eddying of the air within the shell 16. If fuel be supplied through the pipe 19 this fuel will be caused to intimately mix with the air, and, 85 as the louvres 18 are larger than the others, a forward movement through the nozzle will take place. By properly adjusting the deflector plates 29 complete combustion of this mixture may be had when the same is ignited 90 at the mouth of the nozzle. If at this time the valve 24 be closed then the movement will be slow and a short flame will result. If the valves 24 and 22 be now opened a greater supply of fuel will be obtained from the 100 pipe 19, while at the same time a quicker forward movement of the contents of the shell 16 will take place, so that the flame will be projected to a greater distance from the nozzle, and by properly regulating the adjustment 105 of the various valves and deflector plate all conditions of combustion may be accommodated.

What is claimed as new is:—

1. A carburetor for comminuted fuel comprising an outer imperforate and an inner perforated casing, the two being spaced apart, means for supplying air and comminuted fuel to the inner casing, means for supplying air to the outer casing and means 110 connected with the inner casing for directing the discharge of comminuted fuel at any desired angle.

2. A carburetor for comminuted fuel comprising an outer imperforate casing, means 120 for supplying air thereto, an inner casing concentrically disposed relative to the outer casing and providing with openings of different areas, means for supplying air and comminuted fuel to the inner casing, a nozzle 125 carried by the latter casing, and means at the exit end of the nozzle for directing the discharge of the comminuted fuel at different angles.

3. A carburetor for comminuted fuel com- 130

prising an outer imperforate and an inner perforated casing, means for supplying air to the outer casing, means for supplying air and comminuted fuel to the inner casing, a 5 nozzle carried by the inner casing, and valves disposed at the discharge end of the nozzle and arranged to deflect the comminuted fuel at different angles.

4. In a device of the class described, an 10 elongated mixing chamber, means for creating a series of jets of air transversely of said chamber, a duct for conveying a stream of powdered fuel longitudinally of said chamber, a valve surrounding said duct, an air 15 chamber having a communication with the mixing chamber controlled by said valve, and an outlet from the end of said chamber remote from the fuel duct.

5. In a device of the class described, a 20 mixing chamber, an air chamber surrounding the mixing chamber, the wall between said chambers being perforated to create transverse jets of air in said mixing chamber, a duct leading into one end of said mixing chamber, a nozzle for supplying a jet of air to said duct, a supplemental opening connecting said mixing and air chambers, and a hand-operated valve for controlling said connection.

30 6. In a device of the class described, an elongated mixing chamber, an air chamber

surrounding the same, the walls separating said fuel and air chambers being perforated to provide transverse jets of air in said mixing chamber, connections for supplying air 35 to the air chamber, a duct for supplying fuel to the mixing chamber concentric with and at one end thereof, a nozzle for supplying air to said duct to force fuel therefrom, an 40 annular opening surrounding said duct between the same and the wall of the mixing chamber whereby additional communication between the air and mixing chamber is afforded, and a valve controlling said opening. 45

7. In a device of the class described, an elongated cylindrical mixing chamber having openings distributed longitudinally and peripherally in the cylindrical wall thereof, the openings being inclined with reference 50 to the axis of the chamber, an air chamber surrounding the mixing chamber, means for forcing air under pressure into the air chamber, a fuel supply pipe for powdered fuel opening axially into the mixing chamber at 55 one end thereof, means for injecting air into the fuel supply pipe to force the fuel longitudinally of the mixing chamber, and a connection from the other end of the mixing chamber to the burner. 60

In testimony whereof I affix my signature.
HARRY B. PRUDEN.
